UNITED STATES PATENT OFFICE.

JAMES J. BARRY, OF GLOUCESTER, MASSACHUSETTS.

MEANS AND METHOD OF TREATING CRUSTACEA.

Application filed April 30, 1927. Serial No. 187,785.

This invention relates to means and method of treating Crustacea, and the objects of the invention are to provide an improved means and method of separating the abdominal articulated appendages of Crustacea from the remainder of the body consisting of head and thorax; to perform this operation by machine; to obtain rapid and automatic operation of such machine; to simultaneously break the shell and sever the two parts at the juncture of the thorax and abdominal appendage; to discharge the two parts invariably into separate receptacles; to obtain a continuous operation of the machine; to automatically introduce the Crustacea always in one direction, for instance, head first; in such case to automatically grip the head and thorax and retain the grip until after breaking the appendage; to automatically release and discharge the gripped portion which in the instance shown is said head and thorax; to secure simplicity of construction and operation; and to obtain other advantages and results as may be brought out in the following description.

Referring to the accompanying drawings in which like numerals of reference indicate similar parts throughout the several views, Figure 1 is a side view of a machine embodying my invention;

Figure 2 is a sectional view on line 2—2 of Figure 1;

Figure 3 is a view on greater scale than in Figure 1, showing the gripping means in operation;

Figure 4 is a view similar to Figure 3, showing the gripped crustacean in position where it has been broken and the head and thorax still retained in the gripping means;

Figure 5 is a view showing the gripping means released; and

Figure 6 is a plan of a portion of the machine showing several of the gripping means in closed or gripping position at the ends of the chutes by which the Crustacea are supplied to said gripping means.

In the specific embodiment of the invention illustrated in said drawings, the reference numeral 1 indicates an appropriate base or standard, having bearings 2 for rotatably mounting a substantially horizontal shaft 3 which may be continuously rotated by suitable means such as electric motor 4 properly geared thereto. Mounted on said shaft 3 is a substantially radially projecting arm 5. This arm may be duplicated at several

different angular positions about the shaft, as shown in Figure 1, and may be duplicated by others along side of itself as shown in Figure 6, thus providing a series of the arms around the shaft and a series of series along the shaft. While perhaps this duplication of arms will conduce to the smoother and more efficient operation of the machine, it is deemed within the scope of the invention to employ a single arm if so desired or duplicate the same in any arrangement found most expedient or desirable. For brevity, I will describe the machine as if it did have but one arm since they have all been shown alike.

Each arm preferably is in the nature of a leaf-spring, to the extent, at any rate, that a resiliency exists between the outer end portion of the arm and the shaft to which the inner end is attached or from which the arm is actuated. Except as interfered with by some obstruction, the arm will revolve with the shaft, but when the outer end of the arm is hindered, the shaft continues to rotate thereby flexing the arm which will ultimately snap past the obstruction and regain its normal position with respect to the shaft. The outer end of each arm is equipped with a suitable crustacean gripping means 7, more fully described below, which, when the arm is sloping with its free or outer end somewhat above a horizontal position, registers with a delivery chute 8 down which the Crustacea are fed by gravity or otherwise. Upon receipt of a crustacean in said gripping means on the end of said arm, said gripping means closes and grips the crustacean, and as I have shown the Crustacea fed to the machine head first, they will be gripped in this instance by the head and thorax with the abdominal articulated appendage projecting beyond the end of said arm and gripping means.

Meanwhile the shaft has continued to rotate, and the obstruction, shown as pintles 9, which has held the outer end of the arm in registration with the chute is ultimately passed by the flexing action of the arm, so the arm snaps past said pintles to recover its normal relation with respect to the shaft. The path of revolution of said arm is thus rapidly recovering itself, is upwardly to a substantially vertical position as shown in the drawings, at which point a ledge or obstruction 10 is positioned against which the crustacean strikes with considerable force. The blow thus struck is sufficient

to cause, in the instance shown, the appendage to break off and pass onto a chute 11 provided beyond the ledge for reception of the appendages as they are thus broken off 5 and to discharge them as seen fit into receptacles or otherwise dispose of the same preparatory to or as part of the operation or operations to be performed upon them in packing or other treatment thereof. The 10 arm 5, with contained head and thorax, again snaps past this obstruction and comes to a substantially horizontal position as shown in Figure 1, at which time the gripping means is opened and the portion of the crustacean 15 is dropped to another chute 12 for such disposal or use as may be found desirable or expedient. The arm then passes around to its starting position again, when it receives another crustacean, the gripping means closing 20 upon the same; and the several operations above described are repeated.

It may be here noted that by employment of the series of arms around the shaft, that as one arm snaps past or becomes freed from 25 the feed chute, another arm is substantially in position thereunder, and is properly timed to arrive in position and have its gripping means close as the next crustacean slides into place. Each crustacean will 30 therefore operate to hold the others back until the first in line has been suddenly removed, when the next in line automatically moves forward into the gripping means which arrives at that moment in its cycle of 35 operation. I thus avoid the necessity of other holding and trip means for the Crustacea in the chute.

Referring now in greater detail to the specific showing of parts, which have been 40 illustrated herein, for purpose of being definite as to at least one operative construction, the gripping means 7 is preferably a semi-tubular member 13 transversely pivoted, as at 14, at one end of itself to the arm 5. Said member 45 is arranged to normally extend longitudinally of and lie over the end portion of arm 5, the pivoted end of said member being the end thereof toward the shaft 3. A leaf spring 15 is shown secured to said 50 arm and overlying said member to maintain said member in downward or closed position under normal conditions. If so desired, the end of the arm 5 underlying said semi-tubular clamp member 13, may be turned 55 up at its edges so as to provide a similar and co-operating clamp member 16 between which the head and thorax of the crustacean may be enclosed, and gripped in the instance where the Crustacea are fed in headfirst. It 60 is to be noted, however that the invention is not limited to use in this manner, as the Crustacea may be fed either way.

For temporarily holding the pivoted gripping member 13 swung open after discharge of one crustacean and until ready to

grip the next, I provide a shoulder 17 in connection with said member adapted to be engaged by a detent 18 pivoted, as at 19, to the arm 5. As shown, the shoulder 17 may be part of a cam-like member 20 secured 70 to the trunnion or pivot 14 forming part of the gripping member. When the gripping member is swung open, said cam-like member necessarily turns with it, and the hooked end of detent 18 rides over the cam surface 75 and ultimately drops down over the shoulder. A tension spring 21 between said detent and the arm 5 keeps the detent in engagement with said shoulder until some positive means, such as a fixed trip 22 lifts 80 the detent. Said fixed trip is properly positioned to secure a closure of the gripping means while the arm 5 is still relayed by pintles 9.

To overcome the closing action of leaf 85 spring 15 on the gripping member 13 and open said gripping member, I provide a lever 23 in fixed connection therewith, as upon the pivot or trunnion 14. As the arm 5 swings to a position shown in the drawing as substantially diametrically opposite the starting 90 position, a trip 24, fixed with respect to the base of the machine, is engaged by said lever, and as the arm proceeds, the lever is accordingly swung until detent 18 engages shoulder 95 17 as above described.

It may be added, by way of interest, that although the machine is adapted to use the Crustacea generally, it will probably be utilized more often with one specie of Crustacea, namely, shrimp, which are now generally broken by hand and only the tail portion or appendage packed or used, while the body portion is thrown away. Furthermore, it is to be understood that the showing herein 105 is for purposes of being definite as to the fundamental invention and various changes and modifications may be made in the steps of the process and details of construction without departing from the spirit and scope 110 of the invention, and I do not wish to be understood as limiting myself to the specific parts or arrangement thereof shown and described except as set forth in the following claims when construed in the light of the 115 prior art.

Having thus described the invention, I claim:

1. A machine having an obstruction, and means for retaining a portion of an article to be broken and throwing said article forcibly against said obstruction thereby breaking said article and separating the broken parts.
2. A machine having an obstruction, a swinging arm adapted to carry an article to be broken, and means for swinging said arm to forcibly strike said article on said obstruction for breaking said article.
3. A machine having an obstruction, a

- swinging arm, gripping means on said arm for temporarily securing thereto an article to be broken, and means for swinging said arm to forcibly strike said article on said obstruction for breaking said article. 5
4. A machine having a shaft, a substantially radially projecting arm from said shaft, the outer end of said arm adapted to be resiliently displaced with respect to said shaft when obstructed, and means for temporarily obstructing said arm for creating resilient tension and suddenly releasing said arm to obtain accelerated swinging thereof for a portion of its path of movement. 10
5. A machine having a shaft, a substantially radially projecting arm from said shaft, and the outer end of said arm adapted to be resiliently displaced with respect to said shaft when obstructed, means for temporarily obstructing said arm, means for feeding Crustacea individually to said arms during the period of obstruction of said arm, and means for automatically gripping said Crustacea on the arm when fed thereto. 15
6. A machine having a shaft, a substantially radially projecting arm from said shaft, the outer end of said arm adapted to be resiliently displaced with respect to said shaft when obstructed, means for temporarily obstructing said arm, means for feeding a crustacean to said arm during the period of obstruction of said arm, means for automatically gripping said crustacean on the arm when fed thereto, said arm thereafter releasing from said obstructing means and swinging for a portion of its path of movement with accelerated motion, and another obstruction in said path of accelerated motion of the crustacean to violently strike and be broken thereby. 20
7. A machine having a shaft, a substantially radially projecting arm from said shaft, the outer end of said arm adapted to be resiliently displaced with respect to said shaft when obstructed, means for temporarily obstructing said arm, means for feeding a crustacean to said arm during the period of obstruction of said arm, means for automatically gripping said crustacean on the arm when fed thereto, 25
- shaft when obstructed, means for temporarily obstructing said arm, means for feeding a crustacean to said arm during the period of obstruction of said arm, means for automatically gripping said crustacean on the arm when fed thereto, said arm thereafter releasing from said obstructing means and swinging for a portion of its path of movement with accelerated motion, and another obstruction in said path of accelerated motion of the crustacean to violently strike and be broken thereby. 30
8. A machine providing a swinging arm in which a crustacean is adapted to be carried, an obstruction against which the crustacean may be violently struck, gripping means on said arm comprising a swinging member adapted to open and close, means for holding said gripping member normally closed, and a detent for holding said gripping means open for a portion of the path of movement of said arm. 35
9. A machine providing a swinging arm in which a crustacean is adapted to be carried, an obstruction against which the crustacean may be violently struck, gripping means on said arm comprising a swinging member adapted to open and close, means for holding said gripping member normally closed, means for automatically swinging said member open, and a detent for holding said gripping member open for a portion of the path of movement of said arm, means for feeding a crustacean to said arm during the period said gripping means is held open, and means for tripping said detent and permitting said gripping member to close on said crustacean. 40
